CLAIM

The ornamental design for a curved shoe for in-line sander, as shown and described.

DESCRIPTION

FIG. 1 is a perspective view of the curved shoe for in-line sander showing my new design, with an in-line sander shown in broken lines for illustrative purposes only;

FIG. 2 is a top plan view thereof;

FIG. 3 is a side elevational view thereof;

FIG. 4 is a bottom plan view thereof; and

FIG. 5 is an end elevational view thereof, the opposite end being identical.
